UNITED STATES PATENT OFFICE.

TOMMASO DONATO, OF NEW YORK, N. Y.

DEVICE FOR CONVERTING MOTION.

SPECIFICATION forming part of Letters Patent No. 231,547, dated August 24, 1880.

Application filed March 26, 1880. (Model.)

To all whom it may concern:

Be it known that I, TOMMASO DONATO, of the city, county, and State of New York, have invented new and Improved Devices for Converting Motion, of which the following is a specification.

The object of my invention is to provide a new and improved mechanism for converting reciprocating into rotary motion.

10 The invention consists in a rocking lever having one or two segmental racks attached thereto, which act upon sliding racks having a connecting-rod of a crank pivoted between them, whereby the reciprocating motion of the 15 rocking lever is converted into rotary motion, and the power is greatly augmented by the difference in the leverage of the rocking lever and the segmental racks, and is then transmitted to driving-wheels by intermediate 20 geared wheels.

In the accompanying drawings, Figure 1 is a central longitudinal sectional elevation of my improved mechanism. Fig. 2 is a plan view of the same. Fig. 3 is a partial cross- 25 sectional elevation of the same on the line *xx*, Fig. 1.

Similar letters of reference indicate corresponding parts.

A lever, A, is attached to a shaft, B, pivoted 30 between the two sides of a frame, C, so that the said lever A can be rocked to and fro by means of a connecting-rod, D, attached to the lower end of the lever A. One or more segmental racks, E, the radius of which is much 35 less than the length of the rocking lever A, are rigidly attached to the shaft B, so that they rock with the lever A and engage with the teeth of one or more racks, F, fastened to the top of a frame, G, sliding on a track, H, on 40 the bottom of the frame C. A connecting-rod, I, is pivoted in a recess in the sliding frame G and acts upon a crank, J, of a shaft, K, journaled in the sides of the frame C. A cog-wheel, L, is mounted on the shaft K and en- 45 gages with a smaller cog-wheel, M, mounted on a shaft, N, journaled in the sides of the frame C, and having a fly-wheel, P, attached to one or both ends. The cog-wheel L of the shaft K also engages with a smaller cog-wheel, 50 O, mounted on a shaft, Q, journaled in the sides of the frame C. To the ends of this

shaft Q the driving-wheels R R or pulleys S, for transmitting the motion by means of belts, are attached.

If the mechanism is to be used on a wagon, 55 steam road-wagon, or like vehicle, one end of the same is supported on the driving-wheels R R, and the other end on a pair of independent, loose wheels T T.

A beveled geared wheel, U, is mounted on 60 the shaft Q and engages with a beveled geared wheel, V, mounted on one end of a shaft, W, on the other end of which a propeller-screw, Y, is mounted.

The operation is as follows: The power is 65 applied to the rod D, giving the same a reciprocating motion, which is transmitted to the sliding frame G by the rocking lever A and the segmental and horizontal racks E and F; but as the rocking lever A is much longer 70 than the radius of the segmental rack E, the power is increased in proportion to the difference in length of the lever A and the radius of the segmental rack E. The reciprocating motion of the sliding frame G is converted into 75 a rotary motion by the crank J and the connecting-rod I. The motion and power are transmitted to the shaft N by the cog-wheels L and M and are equalized by the fly-wheels P P. The motion is also transmitted to the 80 shaft Q by the cog-wheels L and O.

Driving-wheels R can be fastened to the shaft Q in case the mechanism is to be used to drive a wagon or other vehicle; or pulleys S can be fastened to the shaft in case the 85 mechanism is to be used to drive other machinery. If it is to be used to propel a ship by means of a screw, Y, the screw-shaft W is operated from the shaft Q by means of intermediate beveled geared wheels U and V. 90

Having thus described my invention, I claim as new and desire to secure by Letters Patent—

1. A mechanism for converting motion and augmenting power, made substantially as herein shown and described, and consisting of a rocking lever and segmental racks attached thereto, of sliding racks upon which the segmental racks act, of a connecting-rod pivoted between the sliding racks, and of a crank and 95 geared wheels for transmitting the motion, as set forth. 100

2. In a mechanism for converting motion and augmenting power, the combination, with the rocking lever A, of segmental racks E, the straight racks F, and the sliding frame G, substantially as herein shown and described, and for the purpose set forth.
3. In a mechanism for converting motion and augmenting power, the combination, with the rocking lever A, of the segmental racks E, the straight racks F, the sliding frame G, connecting-rod I, crank J, geared wheels L and M, and the fly-wheels P, substantially as herein shown and described, and for the purpose set forth.
- 15 4. In a mechanism for converting motion and augmenting power, the combination, with the rocking lever A, of the segmental racks E, the straight racks F, the sliding frame G, con-

nected-rod I, crank J, geared wheels L and O, and shaft Q, with driving-wheels R R or 20 pulleys S S, substantially as herein shown and described, and for the purpose set forth.

5. In a mechanism for converting motion and augmenting power, the combination, with the rocking lever A, of the segmental racks 25 E, the straight racks F, the sliding frame G, connecting-rod I, crank J, geared wheels L and O, beveled geared wheels U and V, shaft W, and propeller-screw Y, substantially as herein shown and described, and for the purpose set forth.

TOMMASO DONATO.
